(57) **CLAIM**

The ornamental design for multimedia keys for a keyboard or similar article, as shown and described.

DESCRIPTION

The U.S. Utility Patent Application entitled Keyboard with More than One Eject Key, a user key and/or regional illumination, 10/683,327, and filed on 10 October 2003 is incorporated herein by this reference.

FIG. 1 is a perspective view of multimedia keys for keyboard showing the design.

FIG. 2 is a top plan view of the multimedia keys.

FIG. 3 is a front elevation view of the multimedia keys.

FIG. 4 is a right side elevation view of the multimedia keys.

FIG. 5 is a left side elevation view of the multimedia keys.

FIG. 6 is a rear elevation view of the multimedia keys; and,

FIG. 7 is a bottom plan view of the keyboard in FIGS. 1-6. The broken lines in FIGS. 1-7 showing other keys and structure of the keyboard are for illustrative purposes only and form no part of the claimed design.
